BOOK MATCH DISPENSER

Burton H. Locke, Framingham, Mass.

Application April 10, 1951, Serial No. 220,201

3 Claims. (Cl. 312—42)

1

This invention relates to improvements in dispensers for book matches and is of the type that can be mounted onto a wall, or other vertical surface, and wherefrom the books of matches may be manually dispensed as required.

The main object of the invention is to provide a container that can be mounted onto a wall, or other upright surface, and wherein a conventional box of book matches may be placed, without alteration thereto except the removal of the paper wrapper therefrom, and wherefrom the books of matches may be manually dispensed one at a time as required until the entire box of books is depleted.

Another object of the invention is to provide a simple one-piece construction that can be completely molded of plastic, glass, or the like, without further finishing requirement, and thereby afford a device that can be inexpensively produced and can thus be offered to the consumer at a relatively low cost.

In order to afford a simple structure, I conceive to utilize the inherent resiliency of the end of the box, in which such matches are normally supplied, to prevent the books of matches from inadvertently dropping from the dispensing aperture and to rely on the inherent limberness of the end of the box to permit the books of matches to be dispensed from the aperture one at a time. I further conceive to provide means to facilitate tearing a small portion, or portions, from the same end of the box in order to afford finger clearance holes in the box to facilitate grasping the book to be dispensed from the aperture.

In the accompanying drawing:

Figure 1 is a front elevation of the dispenser with a conventional box of book matches shown therein by broken lines.

Figure 2 is a side elevation of same.

Figure 3 is a bottom view of same.

Figure 4 is a fragmental front elevation of same showing how the books of matches are dispensed.

Figure 5 is a fragmental side elevation of that shown in Figure 4.

Figure 6 is a front elevation of a modified form of construction.

My improved dispenser comprises a channel-shaped housing 10 comprising a plate portion 11 and two outstanding leg portions 12. The outer edge 13, of each leg 12, is generally flanged outwardly in respect to the housing 10 to afford substantial abutment with a wall 14, or like mounting surface, and an aperture 15 is generally provided in each flanged portion 16 to receive mounting screws 17, or the like, to secure the device

2

against the wall in a vertical position as shown.

The area enclosed by the housing 10, when mounted against a wall 14, is of proper size to freely receive a conventional box of book matches 18 in an upright position so that the two rows of books, which normally comprises the contents of the box, are disposed vertically, as shown in broken lines in Figure 1.

The upper end 19, of housing 10, is open to permit the placing of the box of matches 18 within the channel enclosure while the lower end 20 of same is at least partially closed to prevent the box from dropping from the enclosure. The box is placed in the channel enclosure with the open face outward and the books of matches are retained in the box by the plate portion 11 of the channel.

The said lower end 20, of housing 10, is inclined outwardly and downwardly for the purpose of permitting the outer edge of the lower book of matches to be manually tipped downwardly to a position "A," shown by broken lines in Figure 5, where they can be dispensed out through an aperture 21 provided at the said end 20, of housing 10. The aperture 21 is extended entirely across the plate portion 11, of housing 10, so that the books from both vertical rows, or tiers, of books can be dispensed by tipping the outer edge of the bottom book in each tier downward and then sliding the book out through aperture 21.

A plurality of vertically disposed slots 22 are connected to aperture 21 and extend a suitable distance upwardly in plate 11 to permit a portion of the books in each tier to be contacted by a person's finger for the purpose of urging the books downward should the books become inadvertently wedged or otherwise held up in the enclosure above the dispensing aperture 21. The slots 22 could be replaced by a wide slot 23 positioned at the center of plate 11, as shown in Figure 6.

However, a plurality of slots, such as shown in Figure 1, affords a center guide 24 for the books which helps to retain them within the housing and is thus considered the preferred construction.

A slot, or opening, 25 connects aperture 21 and extends a relatively short distance up the inclined bottom 26, of housing 10. The edges of slot 25 are generally substantially sharp, or serrated, or both, to render the said edge suitable to tear a small portion 27, to the outline of the slot 25, from the end of the box in order to afford an opening in the end of the box to clear a person's finger or thumb when grasping the bottom face of the lower book to dispense the book through the aperture 21. The center portion 28,

of the lower end of the match box, will spring downward sufficiently to permit the tearing thereof around the edge of slot 25.

In dispensing the lower books, the end of the match box is sprung downwardly sufficiently to permit the lower book in either tier to be dispensed out through aperture 21, as shown by broken lines 29. After the book has been dispensed and the bottom end of the box released, the said end of the box will spring back sufficiently to uphold the remaining books above the aperture 21 so that the next book will not inadvertently drop from the said aperture. That is, I utilize the inherent limberness of the end of the box to permit the dispensing of the lower book from either tier and then the resiliency thereof to retain the remaining books within the housing thereafter.

A plurality of slots 30, as shown in Figure 6, could be provided in the bottom 27, of housing 10, without departing from the invention. However, it appears that a single slot 25 would serve as well and a single slot would require only the tearing of a single portion from the end of the box and is thus considered the preferred construction.

Although I contemplate molding the dispenser of plastic, or the like, it could be formed of sheet metal without departing from the scope of the invention.

I do not wish to be confined to the exact details as the same are susceptible of modification without departing from the spirit or scope of the invention.

By providing a structure that utilizes the end of the match box in the manner described above, I eliminate the necessity of providing other parts that will retain the books of matches in the housing and that will also permit the books being dispensed as required. Therefore, I afford a simple one-piece device that is inexpensive to produce.

I claim as my invention:

1. A dispensing container for book matches comprising a channel-shaped housing disposed to freely receive and house a conventional box of book matches against a surface when mounted on said surface, the free edge of each leg of the channel section forming said housing being formed outwardly and having means to receive support for the container against the said surface, one end of said housing being open to permit the insertion of a box of book matches endwise within the same after the container is mounted against the said surface, the other end of said housing being inclined and substantially closed to prevent the box of matches from passing therethrough, a dispensing aperture extending across the outer face of said housing at the last described end thereof, a plurality of spaced slots extending longitudinally in the said outer face of said housing and connecting the said aperture, an opening in the inclined closed end of said housing and connected to the said aperture, the said opening having a suitable severing edge to facilitate severing a portion from an end of any conventional book match box that may be inserted in the said

housing for the purpose of dispensing books of matches therefrom.

2. A dispensing container for book matches comprising a channel-shaped housing disposed to freely receive and house a conventional box of book matches against a surface when mounted on said surface, the free edge of each leg of the channel section forming said housing being formed outwardly and having means to receive mounting support for the container against the said surface, one end of said housing being open to permit the insertion of a box of book matches endwise within the same after the container is mounted against the said surface, the other end of said housing being inclined and substantially closed to prevent the box of matches from passing therethrough, a dispensing aperture extending across the outer face of said housing at the last described end thereof, at least one slot extending in the said outer face of said housing and connecting to the said aperture, at least one opening in the inclined closed end of said housing and connected to the said aperture, any said opening having a severing edge to facilitate severing a portion from an end of any conventional book match box that may be inserted in the said housing for the purpose of dispensing books of matches therefrom.

3. A book match dispenser comprising a housing suitable to support a conventional box of book matches vertically on end with the books of matches gravitated face to face in a plurality of vertically disposed rows in said box in the manner they are normally packed, means to attach said housing against a vertical support, the top of said housing being open to permit the insertion of a conventional box of book matches within the housing, the bottom of said housing being substantially covered and being inclined outwardly and downwardly in respect to said support, a dispensing aperture extending across the outer face of said housing at the lower edge thereof, and at least one slot in the said outer face of the housing, all such slots being disposed to extend upwardly from said aperture and to terminate in the said housing, at least one notch in the outer edge of the inclined bottom of said housing, any said notch being connected to the said aperture and having edges suitable to facilitate severing a portion from the lower end of any conventional book match box that may be inserted in the said housing for the purpose of dispensing books of matches therefrom.
